Inventor
H. H. Hull,

By Clarence O'Brien

Attorney

UNITED STATES PATENT OFFICE.

HOMER H. HULL, OF FRUITPORT, MICHIGAN.

WIRE TIGHTENER.

Application filed April 12, 1926. Serial No. 101,415.

The present invention relates to improvements in wire tighteners and has for its principal object to provide an implement which may be readily and efficiently used for tightening a wire around a hose, barrel, box or the like.

One of the important objects of the present invention is to provide a wire tightener which is simple in construction, inexpensive, 10 strong and durable and further well adapted to the purpose for which it is designed.

Other objects and advantages of this invention will become apparent during the course of the following description taken in 15 connection with the accompanying drawing.

In the accompanying drawing forming a part of this application and in which like numerals designate like parts throughout the same:

20 Figure 1 is a side elevation of the wire tightener embodying my invention, parts being broken away and showing the implement in use.

Figure 2 is an edge elevation of the swivel head and the internally threaded sleeve member showing the same associated with the threaded shaft, and

25 Figure 3 is a fragmentary detail showing the connection between the upper end of the 30 threaded shaft and the head member.

In the drawing wherein for the purpose of illustration is shown the preferred embodiment of my invention, the numeral 1 designates generally my improved wire tightener, 35 the same comprising the screw threaded shaft 2. A head 3 is swivelly supported on the upper end of the screw threaded shaft as indicated at 4 with reference more particular to Figure 3 of the drawing. This head 3 tapers gradually toward its upper end as is clearly illustrated in the several figures in 40 the drawing. A pair of upstanding projections or lugs 5 are formed on the upper end of the block 3 by cutting away the intermediate portion 6 thereof. A channel or 45 groove 7 is formed in each of the side edges of the block, and the projections 5 are formed also with the channels or grooves 8 for a purpose to be hereinafter more fully described.

50 A block 9 is provided with the sleeve 10 on the bottom thereof and this sleeve is internally threaded as is also the central opening formed in the block 9 to accommodate the screw threaded shaft 12 whereby the block 55 is adapted for movement along the threaded shaft in the manner to be presently apparent.

A vertical opening 11 is formed in each end portion of the block 9 as clearly illustrated in Figure 1.

An actuating handle 12 is secured on the 60 lower end of the threaded shaft 2 in any suitable manner.

The use of my improved wire tightener may be briefly stated as follows:

The wire is looped around the object which 65 may be a hose, barrel, or the like, and the ends of the wire are crossed and then disposed in the groove 8 in the projections 5 formed on the upper end of the block 3, the 70 ends of the wire being then bent downwardly and disposed within the side grooves or channels 7, the free ends of the wire are then 75 passed through the vertical openings 11 provided therefor in the end portions of the block 9 and the free ends of the wire are then 80 twisted or otherwise secured together as clearly shown in Figure 1.

The upper end of the head will be in engagement with the object around which the wire is to be looped or tightened, and it is 85 obvious that when the handle 12 is turned in one direction, the member 9 will be caused to travel downwardly on the screw threaded shaft 2 thus causing the wire A to be tightened around the object in the proper clamping position. After the wire has been 90 stretched and properly drawn taut around the object, the implement comprising my improved wire stretcher is removed and the free ends of the wire are secured in the usual 95 manner. When wire nails, or hooks are employed in connection with a barrel, it is to be understood of course that the usual staples are driven into the barrel staves, and support the wire around the barrel in a properly clamped position.

The simplicity in which my improved implement is constructed enables the same to be readily and easily operated and will at all 100 times be positive and efficient in carrying out the purposes for which it is designed.

While I have shown the preferred embodiment of the invention it is to be understood that minor changes in the size, shape and arrangement of parts may be resorted to without departing from the spirit of the invention and the scope of the appended claim.

Having thus described the invention, what I claim as new and desire to secure by Letters Patent is:—

110 A wire structure of the class described comprising a threaded shaft, a tapered head

swivelly supported on one end of the shaft, an actuating handle secured on the opposite end of the shaft, a pair of end lugs formed on the smaller end of the head, the tapering 5 sides of said head having guide grooves formed therein, said lugs having guide grooves formed in the ends thereof and merging into the first mentioned guide grooves for the reception of the free ends of the wire which is to be stretched and clamped, a block 10 threaded on the shaft, said block being provided with openings on diametrically opposite sides of the shaft through which the

free ends of the wire are adapted to extend and then bent to prevent the displacement of 15 the same with the said block, the axes of the openings being in parallelism with the axis of the shaft, the distance between the openings being equal to the distance between the adjacent ends of the guide grooves on the 20 head, said block being adapted to move along the shaft upon rotation of the shaft for tightening the wire when the handle is turned in one direction.

In testimony whereof I affix my signature.
HOMER H. HULL.
